POSITIONING MEANS IN CANDLE MAKING APPARATUS

Carl J. Schroeder, Hammond, Ind., assignor to Standard Oil Company, Chicago, Ill., a corporation of Indiana

Application February 24, 1954, Serial No. 412,256

5 Claims. (Cl. 18—24)

1

This invention relates to a candle making apparatus and it pertains more particularly to a means for positioning candle holders over a wax bath in an apparatus for making dipped candles.

In apparatus for making dipped candles having a rotatable horizontal wheel for supporting candle holders and a wax bath positioned below the holders, difficulties have been encountered in properly positioning the candle holders over the wax bath. As a result candles are damaged in the dipping operation by hitting the sides of the bath, and manufacturing costs per marketable candle are high. In addition, the apparatus itself may be damaged and costly frequent repairs may be needed. An illustration of such an apparatus is U. S. 2,647,282.

The main object of my invention is to provide an improved apparatus for dipping candles whereby production costs are reduced to a minimum, speed of production is increased and the uniformity of the product is improved. A further object is to provide a candle dipping apparatus that is essentially automatic in operation. A particular object of my invention is to provide an improved means to aid in the proper positioning of the candle holders over the wax dipping bath. Other objects of the invention will become apparent from the following detailed description of a specific example thereof.

In order to carry out my invention I have provided a wheel which is rotatable on a vertical axis. The holders for supporting the wicks and partly formed candles are attached to the wheel. Positioned around the central axis under the holders is a molten wax bath and a candle cooling means, if desired. The wax bath may be positioned on a platform which may be moved vertically, means may be provided for moving the holders vertically, or a combination thereof may be used. Hold-back means, e. g., spring-loaded convex buffer hold-back means, and means to prevent rebound from the hold-back means to aid in positioning the holders over the wax bath are provided. The entire candle dipping operation may be carried out automatically by means of control mechanisms.

A clearer understanding of the invention and the various features thereof will be gained from the following description taken in connection with the accompanying drawings wherein I have illustrated a preferred embodiment thereof.

In the drawings similar parts are designated by like reference characters throughout the several views.

Figure 1 is a partial plan view of a wheel

2

showing a triple crank and the location of the hold-back means and pawl means associated therewith.

Figure 2 is an elevation of the wheel showing in elevational section the vertically movable wax bath and two holders being cooled.

Figure 3 is a partial plan view showing the triple crank and pawl means and the hold-back means in partial section.

Figure 4 is a partial plan view showing part of one crank arm associated with both the pawl means and the hold-back means which is shown in partial section.

Figure 5 is an elevation view of the pawl means of Figure 4.

Referring to Figure 1, wheel 11 is shown having radially extending arms 12 which support holders 13 for supporting the tops and bottoms of wicks and partially formed candles. Wheel 11 is rotatable on vertical shaft 14. One of the holders is shown positioned over wax bath 15. Triple crank 16 for rotating wheel 11 is shown with some of its supporting structure. Hold-back means 17 and pawl means 18 are shown as to their location by block diagram.

Referring to Figure 2, motor means 19 is shown associated with triple crank 16, which it operates. Two candle holders are shown with cooling equipment which consists of a circular open channel 20 having a perforated inner horizontal partition. Cooling air is introduced via the perforations to aid in solidifying the wax on the wicks and partially formed candles. Cooling channel 20 encircles all holders 13, except the holder positioned over wax bath 15. That is, channel 20 does not quite form a complete circle. Wax bath 15 is shown mounted on platform 21, which can be raised by hydraulic lift 22. Associated with wax bath 15 are lines 23a, 23b and 23c, which can be either flexible hoses or swivel jointed pipes. Lines 23a, b and c are used for introducing or removing wax from tank 15 and for providing heat in the form of hot water or steam to keep the wax molten and at the proper dipping temperature. Wax bath 15 is an insulated rectangular vessel open at the top. Either a coil or a jacket or both can be used to add heat to keep the wax in bath 15 molten and at the proper dipping temperature.

Details are shown in Figure 3 of triple crank 16 associated with hold-back means 17 and pawl means 18. Triple crank 16 consists of three crank arms 24a, 24b and 24c radiating from central hub 25. The external ends of each crank arm terminate in a crank pin 26 and a boss. Crank

55

arms 24a, 24b and 24c are 120 degrees apart, and bosses 27a, 27b and 27c are connected by bars 28 to form an equilateral triangle. Crank 16 rotates on central shaft 29, which is operated by motor means 19, shown in Figure 2. Bosses 27a, 27b and 27c are the portions of the triple crank which contact the hold-back means and pawl means.

Hold-back means

The hold-back means 17 is shown in detail in Figure 3. This mechanism has support 30 as its base. Lever 31 is pivotably attached by a pin 31a to support 30. Attached to lever 31 is roller 32 and rod 33, which is pivotably attached to lever 31 by pin 33a and is approximately perpendicular to lever 31. As a substitute for roller 32 a convex buffer having no moving parts may be used. Cylinder 34 is rigidly attached to support 30 and is so positioned that it is coaxial with rod 33. This cylinder has spring 35 positioned within it and it is closed at its free-end by adjustable plug 36. The free-end or rod 33 is enlarged to form piston 37 which is positioned within cylinder 34, and piston 37 is prevented from escaping from cylinder 34 by shoulders 37a on the cylinder at its open end near the point of attachment to support 30. This piston 37 coacts with spring 35, which resists being compressed by piston 37.

Roller 32 can be mounted on the same axis as the point of attachment of rod 33 with lever 31. However, preferably lever 31 is made wide at its free-end with a knob-like portion 31b for roller 32 to be attached. Such an arrangement allows boss 27c, approaching from a direction about parallel to lever 31, to contact roller 32 substantially head-on upon initial contact and not tangentially. In any event it is preferred that the direction of approach of boss 27c to roller 32 be substantially less than perpendicular to lever 31. Hold-back means 17 offers maximum resistance to boss 27c at the time of initial contact with roller 32, because only a small increment of force is applied by boss 27c to press lever 31 down against the resistance of spring 35. As power is applied to triple crank 16, roller 32 is forced down in a direction toward cylinder 34 and about parallel to the longitudinal axis of cylinder 34, the resistance offered by hold-back means 17 rapidly decreases, since the direction of force being applied by boss 27c to roller 32 is rapidly changing from approximately parallel to lever 31 to perpendicular to lever 31. As boss 27c passes beyond roller 32, roller 32 is forced up by spring 35 to engage a following boss. The tension of spring 35 may be adjusted by plug 36. Normally the tension will be adjusted to be just a little more than sufficient to stop the rotation of the triple crank upon initial contact of a boss with roller 32, when the inertia of the system is greatest, i. e. when the candles are ready for their final dip.

The hold-back means 17 will not work if the parts are so arranged that a boss upon contacting roller 32 does not tend to force lever 31 down toward cylinder 34. Furthermore, reduced effectiveness of hold-back means 17 will result, if a boss approaches roller 32 initially from a direction approaching perpendicular to lever 31.

Pawl means

The pawl means 18 acts in cooperation with hold-back means 17 to position properly holders 13 over wax bath 15. The pawl means 18 comprises a base 38, three pawls 39a, 39b and 39c rotatably connected to base 28, three springs 40

attached one to each pawl, springs 40 being held in place on base 38 by three pins 41a, 41b and 41c and pin 41d which with the aid of springs 40 positions pawls 39a, 39b and 39c. As a boss passes a pawl, a spring causes the pawl to snap back to its normal non-operating position and the boss is prevented from rebounding from hold-back means 17. Multiple pawls are used to prevent triple crank 16 from rotating in the opposite direction even though a boss has not quite contacted hold-back means 17 but has rotated far enough to at least pass pawl 39a.

Refer to Figure 4, which is a different embodiment of the invention wherein hold-back means 17 and pawl means 18 coact with the same boss at the same time. In Figure 3 the hold-back and pawl means are shown coacting with different bosses at the same time. Either embodiment is satisfactory, but the one shown in Figure 3 is preferred to avoid crowding of the parts. In the embodiment of Figure 4, a part of a crank arm and one boss is shown associated with pawl means 18 and hold-back means 17, which is shown except for a portion of cylinder 34 and related parts. Pawl means 18 is rigidly attached to support 30 of the hold-back means.

Figure 5 is an elevation view of pawl means 18 of Figure 4 to aid in showing the arrangement of parts of this device. The three small dotted circles 40a, b and c on pawls 39a, 39b and 39c represent the points of attachment of springs 40 to the pawls.

Operation

After holders 13 with wicks attached have been positioned on wheel 11, the machine is ready to begin the candle dipping operation. After a holder has been positioned over wax bath 15, hydraulic lift 22 raises wax bath 15 to cause the wicks on the holder to be completely submerged in the molten wax which had been previously added to bath 15. Power is then cut-off from lift 22 and wax bath 15 is lowered to its rest position. When bath 15 has reached its rest position, solenoid controls actuate motor 19 which rotates triple crank 16 for $\frac{1}{3}$ of a revolution. One crank pin of the triple crank 16 always engages wheel 11 to cause wheel 11 to rotate with crank 16 and another holder is moved toward position over wax bath 15 while the holder that has just been dipped is moved into cooling channel 20. The mechanisms are so adjusted that motor power is stopped just prior to a boss contacting hold-back mechanism 17, however, the inertia of wheel 11 and triple crank 16 causes the boss to rotate to contact roller 32. The roller 32 offers such resistance to the boss that the rotation of triple crank 16 is stopped and in fact the boss tends to rebound and cause the triple crank 16 to reverse its direction of rotation. It is at this point that multiple pawl means 18 operates to prevent the boss, which has just passed the last pawl 39c, from reversing its direction of rotation. If the timing of power cut-off of motor 19 is slightly off and/or the inertia of the rotating apparatus is not sufficient to quite carry a boss into contact with roller 32 of hold-back means 17, normally the boss will at least have moved far enough to pass the first pawl 39a, and the holder will be sufficiently well positioned over wax bath 15 that it will not strike a side of bath 15 during the dipping operation. A holder which had just been dipped, moves next into cooling channel 20 and continues to rotate in cooling channel 20, where the wax is aided in solidifying by forced

cooled air, until it is time for the next dipping step for that holder.

The sequence of operations described above is repeated with each holder in turn until the candles are built up to the desired size.

While I have described a preferred embodiment of my invention, many modifications and alternatives, arrangements and procedures will be apparent from the above description of those skilled in the art.

I claim:

1. A candle making machine comprising a wheel rotatable on a vertical axis, holders attached to said wheel for supporting wicks and partly formed candles, a wax bath, means for intermittently rotating the wheel to carry said holders into position over said wax bath, means for reciprocally immersing the wicks and partly formed candles thereon in the wax bath during each stop period, spring-loaded convex buffer hold-back means to aid in positioning the holders over said wax bath, and pawl means to prevent said wheel from rebounding when the hold-back means is contacted.

2. The machine of claim 1 wherein said hold-back means is a roller means, and a multiple pawl means is used to prevent said wheel from rebounding when said roller means is contacted.

3. In a candle making machine comprising a wheel rotatable on a vertical axis; holders attached to said wheel for supporting tops and bottoms of wicks and partly formed candles; a wax bath; crank means for intermittently rotating the wheel to carry said holders into position over said wax bath; means for reciprocally immersing the wicks and partly formed candles thereon in the wax bath during each stop period of the wheel; the improvement for positioning of said holders over said wax bath called a hold-back means which comprises a support, a lever having a convex buffer pivotably attached to said support, a rod pivotably attached to said lever, a supported hollow cylinder, a spring positioned within said cylinder and operating with said rod, said buffer being positioned so said crank approaches it at an angle substantially less than perpendicular to said lever with the result that

said crank meets the greatest resistance upon initially contacting said buffer and the resistance decreases rapidly as said crank continues its movement; and pawl means which prevent said crank from rebounding upon contact with said buffer.

4. A candle making machine comprising a wheel rotatable on a vertical axis; radially extending arms on said wheel; holders for supporting the tops and bottoms of wicks and partly formed candles positioned below and supported by said radial arms; a wax bath; multiple crank means for intermittently rotating the wheel to carry said holders into position over said wax bath; means for reciprocally immersing the wicks and partly formed candles thereon in the wax bath during each stop period of the wheel; hold-back means to aid in positioning the holders over said wax bath which comprises a support, a lever pivotably attached to said support, a roller attached to said lever, a rod pivotably attached at an angle of about perpendicular to said lever, said rod having an enlarged free-end in the form of a piston which coacts with a spring positioned within a supported hollow cylinder having an adjustable plug to close one end thereof, said roller being so positioned said multiple crank means approaches it from a direction about parallel to said lever; and multiple pawl means comprising a base, a plurality of pawls pivotably attached to said base and springs attached to said pawls and to said base.

5. The machine of claim 4 wherein said hold-back means and said pawl means act on different bosses.
